UNITED STATES PATENT OFFICE.

HERMAN A. SAFION, OF NEW YORK, N. Y.

DESIGN FOR A LIGHTING-FIXTURE CANOPY.

Application filed December 5, 1925. Serial No. 15,651. Term of patent 3½ years.

To all whom it may concern:

Be it known that I, HERMAN A. SAFION, a citizen of the United States, residing at New York, in the county of Bronx and State of New York, have invented a new, original, and ornamental Design for a Lighting-Fixture Canopy, of which the following is a specification, reference being had to the accompanying drawings, forming part thereof.

Figure 1 is a plan view of a lighting fixture canopy, showing my new design, only

a portion of the ornamentation being fully completed, it being understood that the remainder of the canopy involves a mere repetition of that portion of the design more fully shown; and Fig. 2 is a side elevation thereof.

I claim:

The ornamental design for a lighting fixture canopy, as shown.

HERMAN A. SAFION.
